[57] CLAIM

The ornamental design for a commercial baking oven door,
as shown and described.

DESCRIPTION

FIG. 1 is a perspective view of a commercial baking oven
door showing my new design;

FIG. 2 is a bottom plan view thereof;

FIG. 3 is a top plan view thereof;

FIG. 4 is a left side elevational view thereof;

FIG. 5 is a front elevational view thereof; and,

FIG. 6 is a right side elevational view thereof.

The broken lines showing of the commercial baking oven
housing in FIGS. 1-6 are illustrative of the environmental
structure only and form no part of the claimed design.
